OVERDRIVE CONTROL SYSTEM

Edward M. Claytor, Anderson, Ind., assignor to
General Motors Corporation, Detroit, Mich., a
corporation of Delaware

Application November 20, 1940, Serial No. 366,441

4 Claims. (Cl. 192—3)

This invention relates to systems of control for automobile overdrives and particularly the type of overdrive which employs a planetary gear. When the overdrive is operative, the sun gear of the planetary gearing is held stationary by a pawl, the movement of the pawl is controlled by an electromagnet generally known as the overdrive solenoid. To come out of overdrive the pawl is retracted from the sun gear. The retraction of the pawl from the sun gear is facilitated by interrupting the engine ignition.

In systems of electrical control of overdrives which have been used, an electromagnet relay switch is used to control the overdrive solenoid and a second relay switch controlled by the first relay switch is used to control the ignition. It is an object of the present invention to provide a single relay controlled by a driver operated switch for controlling the overdrive solenoid and for controlling contacts in the ignition circuit, said single relay being provided with means for delaying the return of the ignition controlling contact to normal condition for a predetermined time after the driver operated switch is operated.

Further objects and advantages of the present invention will be apparent from the following description, reference being had to the accompanying drawing wherein preferred embodiments of the present invention is clearly shown.

In the drawing:

Fig. 1 is a wiring diagram illustrating the use of a single relay for controlling an overdrive solenoid and for controlling contacts which are operable to disconnect the ignition apparatus from the current source.

Fig. 2 is a wiring diagram illustrating the use of a single relay for controlling the overdrive solenoid and for controlling contacts in an ignition grounding circuit.

Referring to Fig. 1 an overdrive solenoid 20 comprises a stationary core 21 mounted on a support 22 in alignment with a movable solenoid armature 23 guided by a support 24. Armature 23 receives a nut 25 urged against a stop 26 by a spring 27 located between the nut and the support 24. Armature 23 provides a cavity for receiving a spring 28 located in a state of compression between the nut 25 and a shoulder 29 provided by a pawl rod 30 extending thru the armature 23 of the core 21 and the support 22 and attached at its lower end to a pawl 31 which, as shown in Fig. 2, is adapted to engage a blocker plate 32 and a locking ring of a sun gear 34. When the solenoid is energized to cause the armature 23 to move downwardly toward the core 21 the spring 28 is further compressed to cause the pawl 31 to bear against the blocker 32. During a reversal of torque between engine and transmission the blocker 32 moves away from the lower end of the pawl 31 to allow it to en-

gage the sun gear locking ring 33. Finally the pawl engages a notch in ring 33 and holds the sun gear stationary thus placing the overdrive in operating condition.

5 The armature 23 of solenoid 20 is caused to move downwardly against the action of spring 27 by the combined effect of electromagnet coils 35 and 36 the former being the main attracting coil and the latter the holding coil. During the downward movement of armature 23 the flange of the nut 25 engages a contact blade 37 which separates a grounded contact 38 from a contact 39 connected with coil thus open-circuiting the main attracting coil. However the armature 23 will be held down by the holding coil 36 so long as the latter is energized.

10 The system of control of the solenoid 20 and of the ignition circuit includes a relay 40 having a core 41 having a chromium plated upper end or pole 42 which carries a non-magnetic projection 43. The relay 40 has an armature 44 attached to a terminal 45 and carrying contacts 46 and 47 normally held apart from contacts 48 and 49. When the armature 44 is attracted it strikes against the non-magnetic projection 43 thus holding the armature spaced from the core 42 so that it will not seal against it. Therefore the return of the armature 44 to normal position is not appreciably retarded when the relay 40 is deenergized.

quired for quick acceleration, the switch 65 will be opened.

Switch 65 is connected with a speed responsive switch 70 which may be any suitable form of switch or may be the air vane switch 70. Switch 70 is pivoted at 72 and is held by a spring 73 normally against a stop 74. Switch 71 carries a contact 75 adapted to engage a contact 76 connected to a common terminal 77 with which magnet coils 54 and 36 are connected in parallel. Vane 71 is caused to move clockwise by the impingement thereon of a current of air represented by arrow 77 caused to circulate by the engine cooling fan 18. At a predetermined speed such as 25 M. P. H., for example, switch 70 will be closed. If the regular transmission is in intermediate or high the switch 60 will also be closed. Then current will flow from the battery 58 thru the coil 54 of relay 40 into the coil 36 of solenoid 20. At that instant, however, the solenoid armature 23 will not move downwardly since the energization of the coil 36 is not sufficient to overcome spring 27. Coil 54, being connected with the current source, armatures 44 and 50 will be attracted toward the core 41. The closing of contacts 47 and 49 will complete the circuit from the battery to the ignition switch 80 and thence to the ignition apparatus independent of the contacts 52 and 53. Therefore ignition will be provided altho the contacts 52 and 53 are separated. The closing of contacts 46 and 48 establishes a circuit between the battery 58 and the main attracting coil 35 of solenoid 20. The solenoid 20 then operates to move the pawl 31 against blocker ring 32 (shown in Fig. 2), with yielding pressure upward by the spring 28. When the driver releases the accelerator pedal to allow the engine speed to fall a predetermined percentage below equivalent vehicle speed, there will be a reversal of sun gear rotation which causes the blocker plate 32 to release the pawl 31 and thus to permit the pawl 32 to engage the sun gear locking ring 33 and lock the sun gear against retraction. For further details of this operation reference is made to my co-pending application S. N. 290,356, filed August 16, 1939.

When it is desired to come out of overdrive the driver presses the accelerator pedal down sufficiently to cause the opening of switch 65 thereby disconnecting coils 54 and 36 from the battery 58. Since coil 35 of solenoid 20 had already been disconnected as a result of downward movement of pawl rod 30, armature 23 cannot now be held down since magnetic attraction has been eliminated. Therefore spring 27 will retract the pawl 21 provided pressure is relieved between the sun gear blocking ring 33 and the pawl. This relief of pressure is effected by momentary interrupting the ignition. According to Fig. 1 the decay of flux in relay 40 starts immediately following the opening of switch 65. However, due to the construction of relay 40, the armature 50 will hang on the head 42 for an appreciable time after the pairs of contacts 46, 48 and 47, 49 are separated. During this interval (which is on the order of .1 to .2 second) contacts 52, 53 will be opened while contacts 47, 49 are closed. Therefore the current flow between the battery 58 and the ignition apparatus will be interrupted. During this interval the pressure between the pawl 31 and the sun gear locking ring 33 will be relieved so that spring 27 of the solenoid 20 is able to retract the pawl 31. However, if the pawl 31 should not be disengaged from the ring 33 ignition will be retracted

in any event since the ignition controlling contacts 52, 53 will return to normal condition at a predetermined time following the opening movement of the switch 65.

5 In the form of an invention shown in Fig. 2 I employ a single relay 88 having a core 81 with a chromium plated end or pole and having an armature 82 connected with a terminal 83 and arranged to seal against the chromium plate pole of the core 81 when the armature is attracted. Armature 82 carries contact 84 adapted to engage a contact 85. When contacts 84, 85 are engaged the battery 58 is connected with solenoid terminal 20a with which the attracting coil 35 and the holding coil 36 are both connected. Armature 82 insulatingly supports a contact 86 for engaging a contact 87 connected by wire 88 with spring blade 89 having an insulating button 90 normally bearing against the upper end of the pawl rod 30. Blade 89 carries a contact 91 adapted to engage a grounded contact 92 when the pawl rod 30 moves downwardly. Contact 86 is connected by wire 93 with a point 94 intermediate the primary coil 95 of ignition coil 96 and a timer 97 which is grounded. Primary 95 is connected with battery 58 to a switch 98. The secondary winding 99 of coil 95 is connected with an ignition distributor not shown.

20 Relay core 81 is surrounded by magnet coil 100 in parallel with a resistance 101 employed for the purpose of retarding flux decay in the relay when coil 100 is disconnected from battery 58.

25 The connection of coil 100 with battery 58 is controlled by a system of switches including the gear switch 60, the kick switch 65 and some form of speed responsive switch such as the switch 110 shown in Fig. 2. Switch 110 is of the vane type and employs a vane 111 pivoted and grounded at 112 and urged normally by a spring 113 against a stop 114. Vane 111 carries contacts 115 and 116 adapted to engage respectively with resiliently mounted contacts 117 and 118 connected respectively with terminals 119 and 120. Terminal 119 is connected with contact 67 of switch 65; and terminal 120 is connected with contact 62 of switch 60. The spacing of contacts 115, 117 and contacts 116, 118, and the calibration of the spring 113 are such that contacts 115 and 117 close during the lower speed range, for example 25 M. P. H. and the contacts 116, 118 close in the upper speed range, for example at 55 M. P. H. It is therefore apparent that the driver has control of the overdrive at a speed below the speed at which contacts 116, 118 close. Above that speed the car can not be taken out of overdrive. This is believed to be an advantage since the engine can operate most efficiently to propel the car at the higher speeds when the transmission is in overdrive. Therefore the switch 110 operates to prevent taking the car out of overdrive until the speed falls below a predetermined value, such as 55 M. P. H.

60 65 The going into overdrive takes place in a manner similar to that described in connection to that of Fig. 1. When a speed of 25 m. p. h., for example, has been reached, the switch 110 closes thereby causing relay coil 100 to be connected with battery 58 provided the gear switch 60 is closed which will be the case if the transmission is in intermediate or high condition. The armature 82 will then be attracted downwardly to seal against the core 81 and to close contacts 81 and 85 thereby energizing the overdrive solenoid 20

to condition the pawl for going into overdrive when the driver releases the accelerator pedal sufficiently to permit the engine speed to fall a certain percentage below the car speed. As the pawl 30 moves downwardly contacts 91 and 92 engage; but the ignition coil 96 is not then grounded because the downward movement of armature 82 has separated the ignition controlling contacts 86 and 87.

To come out of overdrive with the system shown in Fig. 2, the operator depresses the accelerator pedal sufficiently to open switch 65. Due to the fact that the decay of flux in the relay 80 is retarded due to the use of the resistance 101 and due to the fact that armature 82 seals against the core 81, the upward movement of the armature 82 to normal position is delayed for an appreciable length of time following the opening of the switch 65. Therefore the reclosing of contacts 86 and 87 as well as re-opening of contacts 84, 85 is delayed. The length of this delay (on the order of .1 to .2 seconds or even longer if desired) is sufficient to allow the engine to pick up in speed sufficiently to deliver positive torque to the overdrive instead of negative torque before the ignition coil is short circuited by the reclosing of contacts 86 and 87. If the car driver should press the accelerator pedal down in the normal way there would be sufficient delay in his foot action to enable the engine to give the positive torque. The system shown in Fig. 2 takes care of the condition when the driver presses the accelerator pedal down as fast as possible thus opening the switch 65 before the engine has had time to accelerate from negative to positive torque. Therefore the system shown in Fig. 2 provides a period of time following the opening of switch 65 during which the solenoid 20 remains energized and the ignition remains operative. While the solenoid 20 is energized, the contacts 91 and 92 are closed; and the instant contacts 86 and 87 reengage the ignition will be short circuited, thereby relieving the pressure between the sun gear locking ring 33 and the pawl 31 in order to facilitate the retraction of the pawl 31 by the spring 37. By the time the pawl 31 has been retracted, contacts 91 and 92 will be separated so that the ignition short circuit is broken and operation of the engine is resumed.

From the foregoing description of the construction and method of operation of the two systems embodying the present invention, it is apparent that I have provided a single relay under the control the driver operated kick switch for controlling both the overdrive solenoid and for controlling contacts which control the ignition apparatus. This relay has means for retarding the return of the ignition circuit controlling contacts to normal status for a predetermined time following the operation of the kick switch. In the case of the system shown in Fig. 1, during this period of delay following the opening of the kick switch 65, of the return of the ignition controlling contacts to normal status, the ignition is inoperative. Operation of ignition is resumed when the contacts return to normal status. In the case of the system shown in Fig. 2, during the delay period of following the opening of the kick switch 65, the overdrive solenoid and the ignition remain operative in order to give the engine opportunity to deliver positive

torque before coming out of overdrive. At the end of the delay period the ignition becomes inoperative when the ignition controlling contacts return to normal status. The restoration of the ignition is dependent upon the retraction of the sun gear locking pawl.

While the embodiments of the present invention as herein disclosed, constitute a preferred form, it is to be understood that other forms 10 might be adopted, all coming within the scope of the claims which follow.

What is claimed is as follows:

1. An overdrive control system comprising a current source, an overdrive pawl, a solenoid for controlling the overdrive pawl, ignition apparatus, a driver operated control switch, and a single relay controlled by said driver operated switch and operable for controlling the overdrive solenoid and for operating contacts which control the status of the ignition apparatus, said relay having time lag provisions for delaying the return of the ignition controlling contacts to normal status for a predetermined time following operation of the driver operated control switch.

2. An overdrive control system comprising a current source, an overdrive pawl, a solenoid for controlling the overdrive pawl, ignition apparatus, a driver operated control switch, a single relay controlled by said driver operated switch and having normally closed contacts establishing an ignition circuit and having normally open contacts for connecting the current source with the overdrive solenoid and having normally open contacts which, when closed, will by-pass the opened (normally closed) ignition controlling contacts, said relay having time lag provisions for delaying the return of the ignition controlling contacts to closed status for a predetermined time following operation of the driver operated switch.

3. An overdrive control system comprising a current source, an overdrive pawl, a solenoid for controlling the overdrive pawl, ignition apparatus, a driver operated control switch, an ignition grounding circuit including a pair of normally closed contacts and a pair of normally open contacts, the latter being controlled by the solenoid, and a single relay controlled by said driver operated switch and including the normally closed contacts of the ignition grounding circuit and including a pair of normally open contacts for connecting the current source with the overdrive solenoid, said relay having time lag provisions for delaying the return of the relay contacts to normal status for a predetermined time following operation of the driver controlled switch.

4. An overdrive control system comprising a current source, an overdrive pawl, a solenoid for controlling the overdrive pawl, ignition apparatus, a driver operated switch, and a relay having a magnet coil connected with the current source through the driver operated switch, and having contacts for connecting the current source with the solenoid, and having contacts for controlling the functioning of the ignition apparatus, and having time lag provisions for delaying the return of the ignition controlling contacts to normal status for a predetermined time following operation of the driver operated switch.
